UNITED STATES PATENT OFFICE.

WILLIAM G. KENDALL, OF NEWARK, NEW JERSEY.

VANITY-CASE CATCH AND PLATE EJECTOR.

Application filed June 25, 1926. Serial No. 118,561.

This invention relates to a catch and ejector for vanity cases and has for an object to provide an improved construction wherein by a push on the catch operating button the ejector will be caused to function to release and partly eject the compact carrying plate.

Another object in view is to provide a simple effective construction of ejector for a compact plate whereby the same may be easily removed without injury to any parts of the vanity case with which it is associated.

A still further object of the invention is to provide a single stamped structure presenting an ejecting cam for releasing and ejecting a compact plate and a catch for normally locking the cover of the vanity case closed.

In the accompanying drawing—

Figure 1 is a perspective view of a vanity case with a plate, ejector and catch embodying the invention shown associated therewith, the lid of the vanity case being shown open.

Figure 2 is a sectional view through Figure 1 on line 2—2, the same being on an enlarged scale and the lid being shown closed.

Figure 3 is a sectional view through Figure 2 on line 3—3.

Figure 4 is a perspective view of a combined catch and plate ejector disclosing certain features of the invention.

Figure 5 is a perspective view showing the front part of the structure illustrated in Figure 4.

Figure 6 is a perspective view similar to Figure 4 but showing a slightly modified construction.

Figure 7 is a sectional view through Figure 8 on line 7—7.

Figure 8 is a fragmentary sectional view through Figure 7 on line 8—8, said figure being similar to the left hand portion of Figure 2.

Figure 9 is a perspective view similar to Figure 6 but showing a modified construction.

Figure 10 is a perspective view of an ejecting cam and associated parts forming a modified construction to that illustrated in Figure 4.

Referring to the accompanying drawing by numerals, 1 indicates the body of a vanity case and 2 a lid hingedly connected to the body in any desired manner. Arranged

in the body 1 is a tray or compact folding structure 3 having pressed out resilient portions 4 for pressing against the compact plate 5 as shown in Figure 2. This structure resiliently holds the compact in place but permits the removal whenever desired. The lid 2 is provided with a pressed out portion 5 whereby a shoulder or notch 6 is formed on the interior surface for receiving the hook end 7 of the catch 8. The catch 8 is preferably integral with the resilient plate 9, which plate has looped ends 10 and 11 which are also resilient to a certain extent whereby the parts are normally held in the position shown in Figure 2. Stamped or pressed from plate 9 is a push button 12, said button being adapted to extend through the aperture 13 in body 1 when the parts are in operative position. Also, preferably integral with plate 9 is an ejecting cam 14 which is formed by having an integral strip bent back on itself to form the lower or horizontal section 15, the inclined or cam section 16 and the supporting or bracing section 17. It is, of course, evident that if desired, the ejecting cam 14 could be made separate and secured in place by rivets, solder or otherwise, though an integral structure has been found satisfactory and the cost of manufacturing the same is small.

When the device shown in Figure 4 is arranged in operative position as shown in Figures 2 and 3, the cam section 16 at the lower end will preferably be almost in contact with the upstanding flange of plate 5 while the catch 8 will be interlocked with the shoulder or notch 6. By pressing slightly on the push button 12, lid 2 is released and may be swung to an open position. By pressing the button 12 inwardly as far as possible, the ejecting cam 14 will function and will, as it functions, raise the plate 5 at one point so that it will be swung upwardly and thereby released from the various resilient holding members 4. By inverting the body 1, the plate 5 and any remaining parts of the compact will drop out by gravity. It will be noted that the looped portions 10 and 11 press against the depending wall or section 18 of tray 3 so that when button 12 is released it will automatically and quickly move back to the position shown in Figure 2. After the plate 5 has been removed, another plate may be inserted and pressed down until it is pinched by the resilient holding members 4 whereby it is held

against accidental removal but in position to be readily raised and loosened by the action of the ejecting cam or ejector 14.

In Figure 6, a modified form is shown 5 wherein the spring 9' is provided with extensions 10' and 11', said extensions meeting and being bent at right angles for forming an ejector 14' having a cam face 16'. By reason of this construction there is some- 10 what less waste of material in forming the ejector though the same operates substantially as the ejector illustrated in Figure 4.

In Figures 7 to 10 inclusive, a further modified construction is disclosed wherein 15 the spring 9'' is not provided with a cam but merely with turned over ends 10'' and 11'' and with a catch and button in a similar manner to that shown in Figure 5. In order to provide an ejecting structure, a 20 special resilient strip of metal 19 is provided having turned over ends 20 and 21 fitting within the ends 10'' and 11''. Cut-away portions 22 and 23 are provided and the metal cut-away is bent for forming an 25 ejector 24 having a cam face 25. The members 19 and 9' are assembled and then placed in position as shown in Figures 7 and 8 whereby the catch 8' may function in a similar manner to the catch 8 and the button 30 12' may function also in a similar manner to button 12.

What I claim is:—

1. A vanity case comprising a body formed with an opening at the front, a lid 25 carried by the body formed with a pressed out portion presenting a shoulder, said shoulder being arranged above said opening when the lid is closed, a tray fitting into said body formed with means for holding a 30 compact including the supporting plate against accidental removal, and a combined plate ejector and catch carried by the body and positioned principally between the front wall of the body, and said tray, said ejector 40 and catch including means forming a catch member interlocking with said shoulder, a push button extending through said aperture, and a cam positioned to slide beneath said compact plate wherein said push button 45 is moved to a certain extent.

2. In a vanity case provided with means for holding a compact plate, cam means carried by the case and forming a mechanically actuated ejector for loosening and 50 partly removing said plate.

3. In a vanity case provided with means

for holding a compact plate in the body thereof, an ejector arranged in said body adapted to eject said plate, and means extending to a point exteriorly of the body for 60 permitting manual actuation of said ejector.

4. In a vanity case a combined catch and ejector, said catch and ejector including a catch member for holding a lid closed, a 65 sliding ejector member for loosening and partly ejecting a compact plate, and means for resiliently holding the plate in a given position.

5. In a vanity case provided with a compact plate an ejector formed with means 70 normally engaging said plate, a spring for holding the ejector in a given position, and means for actuating the spring and ejector for causing the ejector to raise the compact plate.

6. In a vanity case an ejector formed as a cam, a spring for normally holding the ejector in an inoperative position, and manually actuated means for moving the spring and ejector so that the ejector will be forced beneath a compact plate carried by the vanity 80 case.

7. In a vanity case provided with a compact plate an ejector formed substantially triangular in shape and positioned so that one point of the ejector is projecting beneath part of said plate, means acting as a spring for normally holding said ejector from functioning, and a push button associated with the ejector whereby the same may be 90 caused to function and in functioning caused to slide beneath said plate for raising the same.

8. In a vanity case adapted to receive a compact plate, an ejector normally spring 95 held in inoperative position, manually operable means for forcing the ejector into operative engagement with a compact plate, to cause partial ejection of the plate.

9. In a vanity case adapted to receive a 100 compact plate, an ejector normally spring held in inoperative position, manually operable push button means for forcing the ejector under a compact plate in the case to cause partial ejection of the plate.

10. In a vanity case adapted to receive a compact plate, ejector means including a finger piece upon which a direct thrust is adapted to be exerted to render the ejector means operative.

WILLIAM G. KENDALL.
